United States Patent Office

Des. 210,843
Patented Apr. 23, 1968

210,843

PLATE OR SIMILAR ARTICLE

Ryotaro Takeoka, Nishikasugai-gun, Japan, assignor to
Noritake Co., Inc., New York, N.Y., a corporation of
New York

Filed June 26, 1967, Ser. No. 7,609

Claims priority, application Japan Mar. 20, 1967

Term of patent 7 years

(Cl. D44—15)

The figure is a plan view of a plate or similar article showing my new design, a portion of the design being shown between dot and dash lines, and a repeat portion being shown between dotted lines.

The plate is of a conventional configuration when viewed from the side and bottom thereof.

I claim:

The ornamental design for a plate or similar article, substantially as shown and described.
